DIE

Filed Nov. 16, 1936

Fig. 1.

UNITED STATES PATENT OFFICE

2,111,072

DIE

Courtney R. Lindholm, St. Louis, Mo., assignor to
 Independent Die and Supply Company, St.
 Louis, Mo., a corporation of Missouri

Application November 16, 1936, Serial No. 111,064

15 Claims. (Cl. 164—93)

This invention relates generally to dies and particularly to dies of the character employed in performing cut outs and perforating operations upon shoe parts.

- 5 Dies of the character referred to are frequently made in such manner to permit the accomplishment of perforating and cut out operations upon closed or fitted shoe uppers. This necessitates that a working space be provided to accommodate the draping of the upper about the die and the work support, it being understood that such fitted shoe uppers are not of planar configuration but on the contrary are of more or less funnel shape.
- 10 15 In order to accomplish the perforations or cut outs at the desired location provision is made for locating the shoe upper with reference to cutting edges of the die. Such a locating device may be in the form of a gage arranged for co-operation with a marking upon the upper.

In view of the fact that the base structure of such a die is usable with a variety of forms and configurations of cutting devices provision is often made for inter-change of the cutting parts. Upon such inter-changes of the cutting parts of dies of this type, however, it is usually desirable to inter-change the gaging or locating member so as to provide a gage device particularly coordinated with the cutting die. While 20 in dies of this type, as heretofore provided, it has usually been possible to dissociate the gage and substitute a new one in its stead, this has generally necessitated such mechanical operations as the removal and replacement of screws 25 or other permanent connecting devices.

The object of the present invention generally stated, is to provide a die of the character referred to wherein the gaging part may be readily removed and interchanged.

- 30 40 A further object of the invention is to provide a die of the character referred to having an improved work support.

Other objects will become apparent to those skilled in the art when the following description is read in connection with the accompanying drawing in which:—

Figure 1 is a perspective view of a die constructed in accordance with the present invention.

50 Figure 2 is a view in side elevation of the die shown in Figure 1 part being in section to reveal the relation of the parts, and showing a shoe upper in position for operation.

55 Figure 3 is a detail view taken from the rear

of a hinge employed in the embodiment of Figure 1.

Figure 4 is a perspective view illustrating in detail the work support of the die shown in Figures 1 and 2.

5 In accordance with the present invention a die of the character referred to is provided wherein a plate is arranged to overlie the cutting edges of the die in a manner such as to function as a gaging mask. In accordance with the present 10 invention such overlying plate is arranged to be readily disconnected from the base of the die, as for instance by rotating the plate about a hinge connection to a position where the hinges release themselves.

15 The present invention further contemplates the provision of such an overlying plate of such proportions that it extends to and overlies a work support arranged in substantially aligned relation to the cutting members of the die. By 20 placing the work upon the die and work support the operator is enabled to clamp the same in position by pressing downwardly upon the plate thus gripping the work between the work support and the underside of said overlying 25 plate.

Referring now particularly to the drawing for an illustrative embodiment of the present invention, the die may comprise a base upon which a die support 2 is mounted through a plurality 30 of columns 3, so that the die support 2 is elevated above base 1. The die support 2 is arranged to receive and support a die element 4 composed, for instance, of a series of perforating tubes 5. Any suitable means may be provided 35 for retaining die element 4 upon its support 2, but when it is desired to facilitate interchange of die elements in order to adapt the device to different operations, a quickly detachable securing 40 device is advantageous.

45 For example the securing device shown in the prior co-pending application of Christian A. Cadenback, Serial No. 50,245, filed November 16, 1935, may be used.

At one end of base 1 provision may be made 45 for hingedly connecting a gaging plate 6 to the base in such manner that it overlies die element 4. Such hinge connection may be of a type such that the base will yield in response to pressure exerted downwardly upon plate 6. In the 50 embodiments shown such connection is in the form of telescoping members 7 and 8. Member 7 may be provided with an internal spring (not shown) arranged to bias member 8 upwardly relative to member 7. While Figures 1 and 2 55

show the hinge connection only at the right hand rear corner of plate 6, it will be understood that an identical hinge connection is provided at the left hand rear corner thereof, as shown in Figure 3.

In order to accomplish quick detachment and inter-change of plate 6, in accordance with the present invention, the member 8 may be arranged to readily release a cooperating hinge part carried by plate 6. In the embodiment shown in the drawing member 8 is of furcated structure with legs 9 and 10, the former leg being substantially shorter than the latter as shown clearly in Figure 3. Depending from plate 6 is a tenon member 11 arranged to fit into the space between legs 9 and 10 of furcated member 8. The longer leg 10 of furcated member 8 is provided with a hinge pin 12 extending laterally therefrom and arranged to cooperate with an aperture 13 in tenon member 11. The position of hinge pin 12 is such that, in ordinary operation upon opening and closing plate 6 to an extent sufficient for the insertion and release of work parts, tenon member 11 is retained between legs 9 and 10 of furcated member 8; when plate 6 is swung to an extreme position, however, as for instance, the position illustrated in dotted lines in Figure 2 tenon member 11 is then entirely above the shorter leg 9 and hence plate 6 may be released from the hinge connection by sidewise translation thereof (to the right as seen in Figure 1) relative to base 1 until hinge pin 12 is withdrawn from aperture 13.

It will be observed that the hinge connection at the right-hand rear corner of plate 6, shown in Figure 1, is identical with the hinge connection at the left-hand rear corner, shown in Figure 3, so that the shorter leg 9 is, in each instance, on the right-hand side (as viewed in Figure 1) of the longer leg 10. However, it will be understood that the shorter legs might be arranged on the opposite side of the longer legs, the side being immaterial provided both shorter legs are on the same side of their respective longer legs.

In the embodiment shown in the drawing, plate 6 is provided with a cut-out area 14 adjacent the cutting edges of die 4, and is further provided with a gaging tip 15 whereby the work, such as a shoe upper, may be properly aligned with reference to the die, as for instance, by co-ordinating gaging tip 15 with a line of stitching or other marks upon the shoe upper.

In the embodiment shown in the accompanying drawing plate 6 extends forwardly beyond die 4 and overlies a work support 16 as clearly shown in Figure 2. Such a work support 16 may be in the form of a bight rod the ends of which are fitted into sockets in the base 1, as shown at 16, and suitably secured therein, as for instance, by means of set screw 18. Such a bight rod is shown in detail in Figure 4 and is provided with a central bight portion 19 the upper edge of which is at substantially the elevation of and aligned with the cutting edges 5 of die 4.

With the parts arranged in this manner the work, such as a fitted shoe upper 20, may be draped over die 4 and work support 16, and adjusted until properly aligned with reference to gaging tip 15. Such an adjustment of the position of upper 20 may be readily accomplished by the operator who is gripping the upper 20 between work support 16 and the forward end of plate 6. The open center of portion 19 of work

support 16 facilitates such adjustment and clamping since by gripping the assembly, as shown in Figure 2, the tip of one finger is engaged with the lower surface upper 20 so that it may be moved to a limited extent without changing the position of the hand except to release the pinching grip upon plate 6 and work support 16. When the upper is properly positioned, the operator grips the upper between work support 16 and plate 6, and actuates a press to accomplish the cut-out or perforation.

From the foregoing description it will be apparent that the present invention accomplishes its object and provides a die wherein both the cutting element and the gaging device may be readily removed and interchanged, and at the same time provides a die of such character that a fitted shoe upper may be draped over and effectively clamped to a work support while at all times the operator is enabled to make minor adjustment in the relation of the work to the die.

It is apparent that many modifications in the details and arrangements of part of the die herein disclosed will present themselves to those skilled in the art without departing from the spirit of this invention. It is to be distinctly understood, therefore, that the embodiment shown in the accompanying drawing and herein-before described in detail is merely for the purpose of illustration and that the invention is not limited to such illustrative embodiment. It is therefore to be understood that such modifications and the use of such individual features and sub-combinations of features as do not depart from the spirit of this invention are, although not specifically described herein, contemplated by and within the scope of the appended claims.

Having thus described the invention, what is claimed is:

1. A die of the kind described comprising a base, a plate, and a hinge connecting said plate to said base, said hinge being constructed and arranged to release the plate only at a definite angular position.

2. A die of the kind described comprising a base, a plate, and a hinge connecting said plate to said base, said hinge being constructed and arranged to release the plate only at a definite angular position in which the plate is remote from the base.

3. A die of the kind described comprising a base, a plate, and a hinge connecting said plate to said base, said hinge being constructed and arranged to release the plate at an angular position in which the plate is remote from the base but to positively retain the plate in angular positions proximate the base.

4. A die of the kind described comprising a base, a plate, and a hinge connecting said plate to said base, said hinge having a furcated member, one leg of said furcated member being longer than the other, a tenon part carried by the plate and arranged to extend between the legs of said furcated member and a hinge pin connecting said tenon with the longer leg.

5. A die of the kind described comprising, a base, a die elevated above the base, and a work support extending angularly forwardly and upwardly from the base to approximately the elevation of the die, said die and work support being constructed and arranged to have a fitted shoe upper draped thereover.

6. A die of the kind described comprising, a base, a die elevated above the base, a work sup-

port extending angularly forwardly and upwardly from the base to approximately the elevation of the die, and a plate overlying said die and having a cut-out region adjacent the cutting parts of said die.

5 7. A die of the kind described comprising, a base, a die elevated above the base, a work support extending angularly forwardly and upwardly from the base to approximately the elevation of 10 the die, and a plate hinged to said base and overlying said die with a cut out region there adjacent.

10 8. A die of the kind described comprising, a base, a die elevated above the base, a work support 15 extending angularly forwardly and upwardly from the base to approximately the elevation of the die, and a plate extending over said die and said work support.

9. A die of the kind described comprising, a 20 base, a die elevated above the base, a work support extending angularly forwardly and upwardly from the base to approximately the elevation of the die and a plate hinged to said base and extending over said work support.

25 10. A die of the kind described comprising, a base, a die elevated above the base and a work support extending angularly forwardly and upwardly from the base to approximately the elevation of the die and means for clamping work 30 against said work support.

11. A die of the kind described comprising, a

base, a die elevated above the base, and a work support extending forwardly and upwardly from the base to approximately the elevation of the die, said work support being formed of a bight rod the ends whereof are secured to the base.

12. A die of the kind described comprising, a base, a die elevated above the base, and a work support extending angularly forwardly and upwardly from the base, said work support having a planar portion substantially at the elevation of 10 the cutting edges of the die.

13. A die of the kind described comprising, a base, a die elevated above the base, a rod having its ends secured to the base and having a central bight portion at approximately the elevation of the cutting edges of the die.

14. A die of the kind described comprising a base, and a bight rod having a planar portion supported substantially in line with the cutting edges of the die.

20 15. A die of the kind described comprising, a base, a die elevated above the base, a work support extending forwardly and upwardly from the base to approximately the elevation of the die and a plate extending over said die and said work support, said work support having a continuously rimmed centrally open part adjacent an edge of said plate, whereby material clamped between said plate and the rim of said part is accessible through the central opening.
